UNITED STATES PATENT OFFICE.

FREDERICK C. OVERBURY, OF NEW YORK, N. Y., AND HOWARD CARLETON PLATTS, OF RUTHERFORD, NEW JERSEY, ASSIGNEES TO FLINTKOTE MANUFACTURING COMPANY, OF RUTHERFORD, NEW JERSEY, A CORPORATION OF NEW JERSEY.

TILE ROOFING.

1,221,370.

Specification of Letters Patent.

Patented Apr. 3, 1917.

Application filed April 7, 1914. Serial No. 830,210.

To all whom it may concern:

Be it known that we, FREDERICK C. OVERBURY and HOWARD CARLETON PLATTS, citizens of the United States, and residents, respectively, of New York, in the county of New York and State of New York, and of Rutherford, in the county of Bergen and State of New Jersey, have invented certain new and useful Improvements in Tile Roofings, (Case F,) of which the following is a specification.

This invention has for its object to produce a tile roofing, or a roof which when laid has the appearance of one made of clay or composition tiles, which is durable, weatherproof and waterproof, cheap in construction, easy to lay, and which is light in weight and easily packed for shipment.

On the accompanying drawings,—

Figure 1 shows a portion of a roof equipped with the invention.

Fig. 2 represents a section on the line 2—2 of Fig. 1.

Fig. 3 represents a section on the line 3—3 of Fig. 1.

Fig. 4 shows one of the tiles.

For forming the tiles, we may use such material as has heretofore been employed for flat roofing, and therefore may use many of the standard flexible prepared roofing materials now on the market. Such flexible material consists of a base or foundation of wool felt or its equivalent saturated or impregnated with a waterproofing compound such as a hydrocarbon mixture, and coated with a facing or coating of a weatherproof substance such for instance as pitch or bitumen having a relatively high melting point so that it will not be unduly softened by solar heat in warm climates. Such coating or facing may be applied while reduced to a soft and plastic state by heat or when mixed with a volatile solvent. Such a flexible roofing material cannot be bent at sharp angles, particularly in cold weather, after the coating has set or hardened, without danger of the coating cracking or breaking at the bend and thus rendering the material useless as a waterproof and weatherproof covering. When, however, the coating is rendered soft and plastic, either by heat or by the addition of a suitable solvent, the material may be bent at a sharp angle or folded upon itself so as to stretch and elongate the

coating at the bend or fold, and, if it be allowed to set or harden while so stretched or elongated, the folded or bent portion may be again straightened or flattened without danger of cracking or breaking the coating. Hence, in forming the tiles, certain portions are bent or folded under when the coating is plastic. This will be understood without further explanation thereof.

Each tile is formed of a piece or blank of such material, such blank being substantially rectangular. One of these blanks is shown in Fig. 4. Its lower marginal portion is folded back and under the body portion as indicated at 5, the main body of the blank being indicated at 6. It will be observed that the folded portion 5 is not equal in width to the entire blank, there being a reentrant angle formed at 7 by cutting away a portion of the material. Substantially midway between its side edges, the blank is formed, while the coating is in a soft and plastic state, with an upstanding rib 8. This is formed by bending the blank first upon the longitudinal line 9 and then upon the longitudinal lines 10, 10. At the left-hand side of the blank there is a projecting flap or marginal portion 11, which, while the coating is plastic, is bent under the side edge so that when bent under the rib 8 is approximately midway between and parallel to the side edges of the blank. After the blank has been thus formed, it may be straightened out and packed with others for shipment.

The blanks or tiles thus formed are laid in transverse rows upon the roof so as to form alternating curved and angular ribs. The tiles of each horizontal row overlap the tiles of one or more preceding rows; and the tiles of each row overlap the adjacent tiles of the same row. In laying the tiles upon a roof, it is necessary to provide the supporting structure 12 with a plurality of parallel spaced bars or supports 13, which may be made of wood and which extend from the eaves to the ridge so as to support the curved ribs formed by the tiles. With the form of tile shown, the first tile of the row should be placed at the left side edge of the roof, the flap 11 is unfolded, and the upper surface thereof is placed on the top of one of the ribs 13. Fasteners, such as nails or the like, are then driven through the flap, after which the main body of the tile is swung to the

right until the valleys formed by the rib 8 rest upon the roof, with the right hand marginal edge of the tile resting upon the next adjacent bar or support 13. The next tile is 5 then laid in the same manner, the nails or fastenings being driven through the flap 11 and through the side portion of the preceding blank or tile. The tiles are thus laid progressively from left to right until the 10 first row is completed. In this way, the two adjacent side portions of each pair of blanks form a curved rib, and between the several curved ribs there are upstanding angular ribs. These ribs extend from the eaves to 15 ward the ridge. Then the second course is laid in the same manner, the tiles of the second row being placed so as to overlap to a considerable distance the tiles of the first row, this being continued until the roof is 20 covered. When the last row next to the ridge is laid, at which point the supports 13 are slabbed off as indicated at 14, the overlapping side portions of the tiles are flattened so as to overlap to a greater distance 25 the preceding tile, as clearly shown in Fig. 1, so as to form a substantially flat surface instead of a surface containing alternating curved and angular ribs. This flat surface emerges by gradations into the curved surface 30 face as shown in Fig. 1. The ridge may then be covered by overlapping flat blanks formed of the same or similar material as that of which the tiles were formed.

From the foregoing description it will be 35 seen that we have thus provided a roof which is ornamental in appearance and which looks like a roofing formed of clay or composition tile. This appearance is augmented by the fact that the tiles are provided with the folded-under portions at their 40 lower edges, which increase the thickness of the edges so as to form shadows and simulate the solidity and thickness of the clay tiles.

45 In order that the tiles may be made more fire-resistant and in order to increase the esthetic appearance, we preferably mix with the coating material, before it is applied to the blanks or the sheets from which the tiles are formed, a suitable inert pigment, such for instance as ground hematite ore or other equivalent material.

Having thus explained the nature of our 50 said invention and described a way of making and using the same, without attempting

to set forth all of the forms in which it may be made or all of the modes of its use, what we claim is:

1. As a new article of manufacture, a 60 roofing tile consisting of a blank of non-metallic flexible waterproof material having a weatherproof coating, said blank being bent to provide a central upstanding rib, and upwardly and outwardly curved side portions, and being adapted to be elongated 65 or contracted laterally to vary the angularity of the rib and the curvature of said side portions.

2. As a new article of manufacture, a 70 roofing tile consisting of a blank of non-metallic flexible waterproof material having a weatherproof coating, said blank having a folded-under lower portion to appear thick in imitation of a clay tile, and a central upstanding rib and convexly curved side portions, one of said side portions having a fold 75 to provide a flexibly connected lateral flap to lie thereunder, said blank being adapted to be elongated or contracted laterally.

3. A roof comprising a supporting structure, a plurality of spaced bars thereon, a plurality of tiles formed of flexible waterproof material coated with a weatherproof substance, said tiles being arranged in overlapping horizontal rows, each tile having at 80 one side edge a lateral folded-under flap in lapped engagement with the side marginal portion of the next adjacent tile, and fastenings passed through said flaps into said bars and covered by the body portions of the 85 tiles, said tiles being formed with angular ribs located intermediate of said supports, and with side portions arching said supports.

4. A roof comprising a supporting structure, a plurality of parallel spaced bars or supports thereon and projecting from the surface thereof, and a plurality of flexible non-metallic fibrous weatherproof tiles having overlapping convexly curved side portions resting upon and fastened to said supports, and having upstanding angular ribs located between said supports. 95 100

In testimony whereof we have affixed our signatures in presence of two witnesses.

FREDERICK C. OVERBURY.
HOWARD CARLETON PLATTS.
